Inventor:
Edward M. Hewlett,
by *Alfred D. Davis*
His Attorney,

UNITED STATES PATENT OFFICE.

EDWARD M. HEWLETT, OF SCHENECTADY, NEW YORK, ASSIGNOR TO GENERAL ELECTRIC COMPANY, A CORPORATION OF NEW YORK.

LINK INSULATOR.

Application filed September 14, 1921. Serial No. 500,490.

To all whom it may concern:

Be it known that I, EDWARD M. HEWLETT, a citizen of the United States, residing at Schenectady, in the county of Schenectady,

5 State of New York, have invented certain new and useful Improvements in Link Insulators, of which the following is a specification.

The present invention relates to insulators 10 for high potential electric power transmission lines and more especially to strain or dead-end insulators for supporting and anchoring such line wires subjected to excessive longitudinal stresses.

15 Since the introduction of the suspension system of the Buck and Hewlett Patent 925,561, the working potentials of transmission circuits have in many instances been quadrupled and the distances over which 20 electric power is transmitted have been correspondingly increased and at the present time the insulator problem is no longer the limiting factor in electric power transmission. However, the greater potentials and 25 longer distances of transmission have made necessary greater and stronger insulator units especially for sustaining extra high potentials and extra long spans as at crossings of rivers and deep ravines for example.

30 The object of my invention is to provide an improved form of insulator unit for use in suspension systems of electric power transmission which shall be capable of resisting much higher mechanical and 35 electrical stresses than the insulator units heretofore in use on such systems.

One embodiment of my invention is shown in the accompanying drawing in which Fig. 1 is a perspective view of the 40 insulator unit and the metal connectors; Fig. 2 is a transverse central section, and Fig. 3 is a longitudinal axial section thereof.

The insulator consists of a single piece of porcelain or other insulating material having interlinked passageways 1 and 2 disposed therein in planes at right angles to each other for the reception of metallic links 3 of U-shape whereby the stresses imposed on the insulator by the two links pulling in 45 opposite directions will be compressive only and practically confined to the central or body portion 4 of the insulator. The body portion 4 is accordingly made so as to provide a substantial thickness of insulating 50 material between the passageways 1 and 2,

and in order to avoid concentration of the pressure exerted by the metallic links 3, the bearing surfaces are made cylindrical.

In order that the link carried in passageway 1 may be shut in electrically, a barrier 60 wall 5 (see Fig. 1) extends in a U-shape thereabout with the body portion 4 forming a transverse bridge centrally between the parallel portions of the wall while the outer ends of the U-shaped wall 5 are continued 65 into oppositely disposed semi-circular end flanges 6 lying in the same transverse plane and constituting a head. The link in passageway 2 is electrically shut in by two wide cross walls 7 extending transversely to the U- 70 shaped wall 5 and joining at their rear edges with the said semi-circular end flanges 6 and centrally with the body portion 4. The U-shaped wall 5 and the cross walls 7 are disposed somewhat divergently so as to afford 75 approach room to the passageways 1 and 2 and also to facilitate manufacture. The cross walls 7 are made wide enough to extend at their outer edges beyond the crown of the U-shaped wall 5 and thereby form 80 continuous overhangs or eaves 8 at their forward edges.

The metallic U-shaped links 3 are made from round bars flattened throughout the bent portions 9 to provide enlarged bearing 85 contact with the cylindrical surfaces of the passageways through the insulator and their ends are upset to form heads 10 to afford 90 grips for the split clamps 11 which are held together by bolts 12.

When installed a number of insulator units will be connected in series, depending upon the potential of the power current, and their axis will align with the catenary 95 of the wire span and the axis of each insulator will ordinarily be at an acute angle to the horizontal. By installing each insulator with its headed end the higher, any water falling upon the unit will run off 100 from the side upon which it falls without tending to join with the water flowing off the opposite side. Assuming the position of the insulator shown in Fig. 1 to be typical, the water falling upon the left-hand end will run off from the lower edges of 105 the flanges 5 and 6, while that falling upon the right-hand end will run off from the lowermost corners of the cross walls 7 and therefore at a considerable distance from the streams flowing from the other side. 110

By reason of the rain-shedding qualities and the very large creepage surface of my insulator, its resistivity to the escape of electric current thereover is rendered much 5 greater than that of any insulator of corresponding diameter heretofore in use and as a consequence a less number in series will be required for a given potential. On account 10 of the symmetrical distribution of material in my insulator, there is a slight danger of the insulator being injuriously affected by shrinkage strains.

While I have described and shown the best form of embodiment of the invention 15 known to me, I do not desire to be restricted thereto.

What I claim as new and desire to secure by Letters Patent of the United States, is:—

1. An insulator unit having a central or 20 body portion provided with two interlinked passageways, a barrier wall extending in U-shape about one of said passageways, semicircular flanges extending radially from the ends of said barrier wall, and two substantially parallel barrier walls disposed transversely of said U-shaped barrier wall and

adjacent the sides of the second passageway and joined at their rear ends with said radial flanges.

2. An insulator unit having a central or 30 body portion provided with two interlinked passageways, a U-shaped barrier wall extending about three sides of one of said passageways, two transverse barrier walls disposed on opposite sides of the other of said 35 passageways with their outer edges disposed clear of the U-shaped barrier wall and their rear edges united by radial flanges.

3. An insulator unit having a central or body portion provided with two interlinked 40 passageways, a U-shaped barrier wall extending about three sides of one of said passageways, two transverse barrier walls disposed on opposite sides of the other of said passageways, and two semicircular flanges 45 extending radially outward from the ends of said U-shaped wall and joined to the rear ends of the two transverse walls.

In witness whereof, I have hereunto set my hand this 13th day of September, 1921.

EDWARD M. HEWLETT.
